COIN ACTIVATED POOL TABLE

Harvey Heiss, North Miami, Fla., assignor to A.T.I.
Recreation Inc., Miami Lakes, Fla.

Filed Jan. 13, 1972, Ser. No. 217,715

Term of patent 14 years

Int. Cl. D21—01

U.S. Cl. D34—3

FIG. 1

FIG. 2

FIG. 3

FIG. 4

FIG. 5

FIG. 6

FIG. 1 is a top plan view of a coin activated pool table showing my new design;

FIG. 2 is a side elevational view thereof;

FIG. 3 is an end elevational view thereof;

FIG. 4 is a bottom plan view thereof;

FIG. 5 is a side elevational view showing the side opposed to the side elevational view as shown in FIG. 2 of the drawings;

FIG. 6 is an end elevational view taken from the end opposed to the end as shown in FIG. 3 of the drawings.

I claim:

The ornamental design for a coin activated pool table, as shown and described.
